CLAIM

The ornamental design for a sanitary napkin box cover, as shown and described.

DESCRIPTION

FIG. 1 is a front elevational view of a sanitary napkin
box cover showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The fabric pattern fragmentarily shown in FIGS. 1-6, is understood to extend throughout the claimed design.
